CLAIM

The ornamental design for a rack mounted data storage unit for a data processing system, as shown and described.

DESCRIPTION

FIG. 1 is a reduced top, front and right side perspective view of a rack mounted data storage unit for a data processing system showing my new design;

FIG. 2 is a front elevation thereof;

FIG. 3 is a rear elevation thereof;

FIG. 4 is a left side elevation thereof;

FIG. 5 is a right side elevation thereof;

FIG. 6 is a top plan thereof; and,

FIG. 7 is a bottom plan thereof.

The rear elevation is shown for illustrative purposes only. The features shown in the rear elevation are functional features which are not visible during normal use, and form no part of the claimed design.
